(57) **CLAIM**

The ornamental design for a coupler for actuator, as shown and described.

DESCRIPTION

FIG. 1 is a top perspective view of a coupler for actuator showing my new design;

FIG. 2 is a bottom perspective view thereof;

FIG. 3 is a front elevational view thereof; the rear elevational view is the same as the front elevational view;

FIG. 4 is a left side elevational view thereof; the right side elevational view is the same as the left side elevational view; FIG. 5 is a top plan view thereof;

FIG. 6 is a bottom plan view thereof; and,

FIG. 7 is a cross-sectional view thereof taken along the line 7-7 in FIG. 5.

The broken lines show portions of the coupler for actuator that form no part of the claimed design, and the dash-dot-dash broken lines only indicate a border between the claimed area and disclaimed area.
